The ornamental design for a front panel for an autochanger, as shown and described.

DESCRIPTION

FIG. 1 is an isometric view of a front panel for an autochanger showing my new design, the broken line showing of the autochanger is for illustrative purposes only and forms no part of the claimed design;

FIG. 2 is a front elevational view of the front panel for an autochanger of FIG. 1;

FIG. 3 is a top plan view thereof;

FIG. 4 is a bottom plan view thereof; and,

FIG. 5 is a right side elevational view thereof; and,

FIG. 6 is a left side elevational view thereof.

The rear of the front panel for an autochanger is unornamented and forms no part of the claimed design.
